STAPLING MACHINE

Werner Schafroth, Herrin, Ill.

Application January 17, 1958, Serial No. 49,282

Term of patent 14 years

(Cl. D74—1)

Fig. 1 is a side elevational view of a stapling machine, showing my new design,

Fig. 2 is a top plan view thereof,

Fig. 3 is a front elevational view thereof,

Fig. 4 is a rear elevational view thereof, and

Fig. 5 is a perspective view thereof, showing the side opposite to that of Fig. 1.

I claim:

The ornamental design for a stapling machine, substantially as shown.
